UNITED STATES PATENT OFFICE.

GEORGE P. WIGGINTON, OF KALAMAZOO, MICHIGAN, ASSIGNOR TO KALAMAZOO LOOSE LEAF BINDER CO., OF KALAMAZOO, MICHIGAN.

BINDER DEVICE.

1,267,829.

Specification of Letters Patent. Patented May 28, 1918.

Application filed February 2, 1917. Serial No. 146,106.

To all whom it may concern:

Be it known that I, GEORGE P. WIGGINTON, a citizen of the United States, residing in the city and county of Kalamazoo, 5 State of Michigan, have invented certain new and useful Improvements in Binder Devices, of which the following is a specification.

This invention relates to improvements in 10 binder devices.

The main objects of my invention are:

First, to provide an improved binder device which facilitates the use of temporary binders or loose sheet holders and particularly those adapted for machine accounting 15 systems.

Second, to provide an improved binder device which facilitates the handling or manipulation of loose record sheets.

20 Third, to provide an improved binder device which facilitates the handling of temporary binders or loose sheet holders for the manipulation and insertion of sheets therein.

Further objects, and objects relating to 25 structural details, will definitely appear from the detailed description to follow.

I accomplish the objects of my invention by the devices and means described in the following specification. The invention is 30 clearly defined and pointed out in the claims.

A structure which is a preferred embodiment of my invention is clearly illustrated in the accompanying drawing, forming a 35 part of this specification, in which:

Figure I is a perspective view showing one adaptation of my improvements providing a pair of opposed binder member and sheet holders.

40 Fig. II is a vertical longitudinal section of my improvements adapted as in Fig. I, with a binder and sheets disposed therein.

Fig. III is a detail side elevation showing the binder of Fig. II adjusted to closed position.

45 Fig. IV is a perspective view of the separated holder members employed in the adaptation shown in Figs. I, II and III.

Fig. V is an enlarged detail section on a 50 line corresponding to line 5—5 of Figs.

II and III, showing the connection for the holder members shown in Fig. IV.

Fig. VI is a perspective view of another adaptation of my invention providing a U-shaped binder holder. 55

Fig. VII is a perspective view of the separated members constituting the adaptation of Fig. VI.

Fig. VIII is a detail vertical longitudinal section of the adaptation of Fig. VI with a 60 binder disposed therein.

Fig. IX is a detail vertical longitudinal section corresponding to that of Fig. VIII adjusted to another position in which one of the binder members is supported in a 65 horizontal position, the sheets being arranged as for the closing of the binder.

Fig. X is a detail side elevation showing the binder closed.

Fig. XI is a detail longitudinal section 70 corresponding to that of Fig. VIII showing another type of binder arranged in the holder.

Fig. XII is a detail side elevation with the device adjusted to support one of the 75 binder members in a horizontal position, the sheets being adjusted as for the closing of the binder.

Fig. XIII is a detail longitudinal section 80 showing the binder closed.

In the drawing similar reference characters refer to similar parts throughout the several views, and the sectional views are taken looking in the direction of the little arrows at the ends of the section lines. 85

Referring to the drawing, the binder illustrated in Figs. II, III, VIII, IX and X is that shown in my Patent No. 1,174,458, March 7, 1916, and comprises a pair of covers 1, 1, having clamping members 2, 2, 90 pivotally mounted thereon and provided with sockets 3 for the removable posts 4. Binding strips 5 extend between the covers which are provided with suitable adjusting means whereby the binding may be retracted and extended, the adjusting means not being shown. The binder constitutes, speaking generally, a pair of separably associated binder members. 95

The binder shown in Figs. XI, XII and 100

XIII is of the sectional post type and comprises a pair of covers 6, 6, having clamping members 7, 7, adapted to receive posts 8 which are detachably secured therein. The means for securing the posts are not illustrated or described in detail, as such means form no part of this invention. This binder also comprises a pair of separably associated binder members.

10 The sheets 9 are perforated to receive the posts and are also preferably slotted at 10 to receive the binding strips when used in the binder shown in my said patent. The slots 10 are also adapted to coact with guide members to facilitate the alining of the sheets.

The binders and sheets may be manipulated in the device, as will appear from the following description:—

20 The device comprises 3 holder sections or members, designated generally by the numerals 11, 12 and 13, the sections 11 and 13 being adapted to be associated interchangeably with the section or member 12, the sections or members 11 and 12 being associated to provide the adaptation shown in Figs. I, II and III, while the sections 12 and 13 are associated to provide the adaptation or adjustment shown in Figs. VI, VIII and XIII, 30 inclusive.

I will first describe the sections or holder members 11 and 12 in their adaptation or association shown in Figs. I, II and III. The support member 11 comprises base members 35 14 disposed on edge and having V-shaped recesses in their upper edges for the side member 15 and the end member 16 constituting a binder member or sheet holder adapted to receive one of the binder members with sheets arranged thereon with their inner ends abutting the end member, as shown, for instance, in Fig. II.

The holder or support member 12 comprises a pair of base members 17 on which 45 the side member 18 is mounted and also an adjustable coacting end member 19 which is hinged at 20 to the lower edge of the side member 18. This end member 19 is adapted to be supported upon the base members 17, 50 as shown in Fig. VI or to rest on the base members 14 of the section 11, as shown in Figs. I, II and III, when the holders 11 and 12 are associated. When the holder members are associated in this relation the base members 17 are telescoped with the base members 14 and secured together by the rod 21 which is arranged through holes provided therefor in the base members 14 and holes in the plates 22 secured on the 55 inner sides of the base members 17. These base members 17 are longitudinally slotted at 23 to engage the cleats 24 on the inner sides of the outer base members 14 of the section 11. This provides a secure connect-

ing means for the parts and permits their 65 being readily disconnected as occasion requires.

To accommodate the binding strips of the binder illustrated in Fig. II the end member 16 of the section 11 is provided with slots 70 25 while the end 19 of the section 12 is provided with slots 26 alined with the slots 25 when the holder members 11 and 12 are adjusted into coacting relation. The binding strips drop into these slots, as shown in Fig. 75 II, when the binder is disposed in the support with one binder member in each holder.

To facilitate the alining or the grouping of the sheets on the binder members I provide the sheet guides 27 and 28, the guide 80 27 being detachably mounted on the end 16, while the guide 28 is detachably mounted on the end 19. The details of the mounting for these guides are not illustrated as they form no part of this invention, the mounting being preferably that shown in my application for Letters Patent, filed Nov. 26, 1915, Ser. No. 63,566.

To provide the U-shaped holder illustrated in Fig. VI the members 12 and 13 are 90 associated together. The member 13 comprises a pair of base members 29 connected by the cross piece 30. The side member 31 is hinged at 32 to be adjusted to the upright position shown in Fig. VI or to a horizontal 95 position, as shown in Fig. XII. The base members 29 are provided with tongues 33 adapted to extend into the slots 23 of the base member 17 in which position they are secured by means of the rod 34 arranged 100 through holes in the plates 22 and the holes in the tongues. When secured in this position the side member 31 coacts with the side member 18 and end member 19 in providing a U-shaped holder, or the side member 31 105 may be swung down to a horizontal position constituting an independent binder member holder support, as shown in Fig. IX. The side member 31 is provided with arms 35 which extend under the end 19 and raise it 110 to an inclined position, as illustrated, when the side member 31 is collapsed. The arms 35 are so disposed as to constitute abutments for the binder member arranged upon the collapsed side member. The arms have 115 curved ends so that they slide freely against the under side of the end member 19. When the end member 19 is thus supported it is at right angles to the side member 18.

The side member 31 is supported by the 120 links 37 and 38 pivoted to each other at 39, the link 37 being pivoted at 40 to the side member and the link 38 being pivoted to the base members 29 at 41. Stops 42 are provided to limit the swing of the links.

With the parts assembled and adjusted as shown in Figs. VI and VIII the binder may be arranged therein, as shown in Fig. VIII,

and the sheets shifted from one side to the other as occasion may require.

If desired to support part of the sheets in a horizontal position the device may be adjusted to the position shown in Fig. IX, and the sheets transferred from one binder member to the other.

When it is desired to close the binder the device is preferably adjusted to the position shown in Fig. IX which brings the end member 19 to a position at right angles with the side member 18 to aline the sheets so that the post 4 may be readily inserted and the other binder member adjusted to position 15 and the adjusting mechanism drawn up, as indicated in Fig. X.

To close the binder when the device is adjusted as shown in Figs. I, II and III the sheets are all transferred to the binder member resting in the support member 11 in which adjustment the end 16 is at right angles to the side 15, so that the sheets are properly alined to receive the post. The binder member which has been resting on the support member 12 is then adjusted, as shown in Fig. III, and the binder locked up. In both manipulations the guide members 27 and 28 should be removed before the second binder member is superimposed on the sheets.

In Figs. XI, XII and XIII a post type of binder, heretofore described, is arranged in the support. The device is manipulated for this type of binder substantially the same as has been described when the binder of my said patent is employed.

My improved binder device is also advantageous for the handling or manipulation of loose sheets independently in a loose sheet binder. My improved binder device very greatly facilitates the handling of loose sheets and loose sheet binders in the keeping of records, particularly when it is desired to keep such records on accounting machines, as they are commonly designated. It, however, is of material advantage even where the records are to be kept by hand.

I have illustrated and described my improvements as I have embodied the same in practice. I have not shown certain modifications or adaptations which might be desirable for certain conditions and uses, as I believe the disclosure made will enable those skilled in the art to which my invention relates to embody or adapt the same as conditions may render desirable.

Having thus described my invention, what I claim as new and desire to secure by Letters Patent, is:

60 1. In a device of the class described, the combination of a holder member comprising a base and side and end members mounted thereon in coacting relation, the end member being pivoted for adjustment to an out-

wardly inclined or to a horizontal position, 65 a coacting holder member comprising a base and a side member pivotally mounted thereon and provided with arms adapted when the side member is adjusted to horizontal position to support said adjustable 70 end member in an inclined position, and means for detachably connecting the bases of said holder members.

2. In a device of the class described, the combination of a holder member comprising 75 coacting side and end members, the end member being mounted for adjustment, and a coacting holder member comprising a side member mounted for adjustment and provided with means adapted when the side 80 member is adjusted to one position to support said adjustable end member in an inclined position.

3. In a device of the class described, the combination of a pair of side members, one 85 of said side members being pivotally mounted and a coacting end member pivoted at its edge opposite said pivotally mounted side member, means for supporting said pivotally mounted side member in its erected position, and arms on said side member engaging the under side of said end member to elevate and support it in an inclined relation when said side member is collapsed. 90

4. In a device of the class described, the combination of a pair of side members, one of said side members being pivotally mounted, and a coacting end member pivoted at its edge removed from said pivotally mounted side member, means for supporting said 95 side member in its erected and collapsed position, and means for actuating said end member when said side member is collapsed. 100

5. In a device of the class described, the combination of side members, one of which is pivotally mounted at its lower end, a coacting end member mounted between said side members for tilting adjustment an arm on said pivoted side member engaging said end member to support it in inclined relation to the other side member when said pivoted side member is collapsed, said arm constituting an end member for said collapsed side member. 105

6. In a device of the class described, the 115 combination of side members, one of which is adjustably mounted, a coacting end member adjustably mounted between said side members, operating connections between said adjustable side and end members whereby 120 when said adjustable side member is erected a U-shaped holder is provided and when it is collapsed said end member is supported in an inclined relation to coact with the erected side member, and means brought into position by the collapsing of said side member constituting an abutment therefor. 125

7. In a device of the class described, the

combination of side members, one of which is adjustably mounted, a coacting end member adjustably mounted between said side members so that when said adjustable side member and end member are adjusted to one position a U-shaped holder is provided and when adjusted to another position said adjustable side member is collapsed and said end member is disposed in an inclined relation to the other side member, and means brought into position by the collapsing of said side member constituting an abutment therefor.

8. In a device of the class described, the combination of side members, one of which is adjustably mounted, a coacting end member adjustably mounted between said side members so that when said adjustable side member and end member are adjusted to one position said adjustable side member is collapsed and said end member is disposed in an inclined relation to the other side member, and means constituting an abutment for said collapsed side member.

9. In a device of the class described, the combination of side members, one of which is adjustably mounted, a coacting end member adjustably mounted between said side members so that when said adjustable side member and end member are adjusted to one position a U-shaped holder is provided and when adjusted to another position said adjustable side member is collapsed and said end member is disposed in an inclined relation to the other side member, and means constituting an abutment for said collapsed side member.

10. In a device of the class described, the combination of side members, one of which is adjustably mounted, a coacting end member adjustably mounted between said side members so that when said adjustable side member and end member are adjusted to one position said adjustable side member is collapsed and said end member is disposed in an inclined relation to the other side member.

11. In a device of the class described, the combination of a pair of side members one of which is adjustably mounted, a coacting end member disposed between said side members and pivoted adjacent the other side member so that when said adjustable side and end members are adjusted to one position a U-shaped holder is provided and when adjusted to another position said adjustable side member is disposed horizontally and said end member disposed in inclined relation to the other side member.

12. In a device of the class described, the combination of side members one of which is adjustably mounted, and a coacting adjustably mounted end member disposed between said side members so that when said

adjustable side and end members are adjusted to one position a U-shaped holder is provided and when adjusted to another position said adjustable end member is disposed in an inclined relation to coact with the other side member and provide a trough-like holder, the adjustable side member being supported in a horizontal position.

13. In a device of the class described, the combination of side members, one of which is pivotally mounted at its lower end, a coacting end member mounted between said side members for tilting adjustment, and an arm on said pivoted side member engaging said end member to support it in an inclined relation to the other side member when said pivoted side member is collapsed.

14. In a device of the class described, the combination of side members, one of which is adjustably mounted, and a coacting adjustably mounted end member operatively associated with said adjustable side member so that when said adjustable side member is erected a U-shaped holder is provided and when it is collapsed the end member is supported in an inclined position to coact with the other side member.

15. In a device of the class described, the combination of a pair of side members and a single end member adjustably mounted between said side members so that it may be adjusted to a substantially horizontal position to coact with both side members providing a U-shaped holder or inclined toward one of said side members and coact therewith to provide a trough-like support, the other side member being adjustably mounted so that it may be adjusted to provide a second support independent of such trough-like support.

16. In a device of the class described, the combination of a pair of side members and a single end member adjustably mounted between said side members so that it may be adjusted to a substantially horizontal position to coact with both side members providing a U-shaped holder or to a position inclined toward one of said side members and coact therewith to provide a trough-like support.

17. In a device of the class described, the combination of a pair of side members and a single end member mounted between said side members for tilting adjustment so that it may be adjusted to a horizontal position to coact with both side members providing a U-shaped holder or inclined toward one of said side members to coact therewith providing a trough-like support, the other side member being adjustable to provide a second support.

18. In a device of the class described, the combination of a pair of side members and a single end member mounted between said

side members for tilting adjustment so that it may be adjusted to a horizontal position to coact with both side members providing a U-shaped holder or inclined toward one of 5 said side members to coact therewith providing a trough-like support.

In witness whereof, I have hereunto set

my hand and seal in the presence of two witnesses.

GEORGE P. WIGGINTON. [L. s.]
